FIRE-TUBE BOILER

Howard G. Sawyer, Bayside, N. Y.

Application October 7, 1944, Serial No. 557,643

7 Claims. (Cl. 122—126)

This invention relates to new and useful improvements in a fire tube boiler.

More specifically, the invention proposes the construction of a fire tube boiler characterized by a boiler casing for holding and circulating a quantity of water and having a combustion chamber located in the bottom portion of the casing attached to which a burner is mounted to supply the required heat to heat the water circulating in the boiler casing.

Still further it is proposed to provide a combustion chamber with a downwardly sloping top crown sheet over the top of which the circulating water is adapted to pass and which is sloped downwards so that the circulating water may easily wash sludge deposits off the top face of the crown sheet.

A further object of the invention proposes the provision of fire tubes spaced from each other and extending upwards from the crown sheet to the top of the casing through the circulating water providing additional surface to transmit heat of the burner to the water, heating the same.

Still another object of the invention proposes extending the top ends of the fire tubes through the top wall of the boiler casing and over which a smoke hood is mounted and connected with a chimney for the purpose of conveying smoke from the burner to the chimney.

It is still another object of this invention to provide superimposed baffle plates within the boiler casing one of which has finger portions extending between the fire tubes for the purpose of assisting in circulating the water in the combustion chamber.

Still another object of the invention proposes the provision of a cover sheet of rigid metal engaged upon the crown sheet of the combustion chamber with the provision of a means for moving the cover sheet to strike against the bottom-most baffle plate increasing the angular inclination of this cover sheet and causing it to be slightly vibrated to assist the water in washing the sludge deposits from the top face of this cover sheet.

It is another object of this invention to construct a fire tube boiler which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front perspective view of a fire tube boiler, constructed in accordance with this invention.

Fig. 2 is a rear perspective view of Fig. 1.

Fig. 3 is a view similar to Fig. 2 but being partially vertically sectioned to reveal interior construction.

10 Fig. 4 is a vertical sectional view taken on the line 4—4 of Fig. 2.

Fig. 5 is a vertical sectional view taken on the line 5—5 of Fig. 2.

15 Fig. 6 is a partial enlarged vertical sectional view similar to a portion of Fig. 4, but illustrating a modification of the invention.

Fig. 7 is a horizontal sectional view taken on the line 7—7 of Fig. 6.

The fire tube boiler, according to this invention, includes a boiler casing 10 constructed of metal for holding and circulating a quantity of water 11. The back of the casing 10 is provided with an inlet pipe 12 for the water to be heated and a discharge pipe 13 for withdrawing steam from the boiler casing 10.

20 A hollow combustion chamber 14 is mounted within the bottom portion of the boiler casing 10 and is provided with a downwardly sloping top crown sheet 15. This top crown sheet 15 slopes downwards in order that the water circulating through the water casing may wash sludge deposits from the top of this combustion chamber 14.

25 A plate 16 is secured in position in the front wall of the boiler casing 10 and is provided with an opening aligned with a complementary opening in an adjacent wall of the combustion chamber 14 with a tube 17 located between the openings and in which any of the conventional oil burners (not shown on the drawing) is adapted to be mounted. Further details of the burner will not be given in this specification as these details form no part of this invention. The purpose of the burner is to supply the required heat for heating the water 11.

30 45 The burner may be connected to any source of oil or gas.

A plurality of rectangular fire tubes 18 extend upwards from the crown sheet 15 of the combustion chamber 14 to the top wall of the casing 10. A smoke hood 19 is mounted on the top wall of the boiler casing over the top ends of the fire tubes 18. This smoke hood 19 is adapted to be connected with a chimney outlet and is designed to convey smoke from the combustion chamber 14 to the chimney. In addition heat passing through

the fire tubes 18 will be transmitted through the walls into the water 11 circulating in the casing 10 to assist in heating this water. A narrow baffle plate 20 is mounted in the boiler casing 10 at a position slightly above the high end of the crown sheet 15. A second wider baffle 21 is mounted within the casing 10 over the baffle plate 20. This latter baffle plate 21 has rearwardly extending fingers which project between the adjacent faces of the fire tubes 18. The baffle plates 20 and 21 are provided for causing the water 11 to circulate in the casing 10 in a path from the high end to the low end of the crown sheet 15 to cause a definite washing action across the downwardly sloping face of this crown sheet which will wash all sludge deposits off the crown sheet.

In the modified form of the invention disclosed in Figs. 6 and 7 a means is provided for assisting the water in removing the sludge deposits from the downwardly sloping crown sheet 15 of the combustion chamber 14. In this form of the invention a cover sheet 30 is extended along and is secured above the crown sheet 15. The bottom end of the cover sheet 30 is attached to a rod 31 extended across the boiler casing 10. One end of the rod 31 is rotatively extended through a packing gland 32 mounted on the side wall of the casing 10 and is provided with a downwardly extending finger portion 33 by which the rod 31 may be gripped to be turned. This will cause the cover sheet 30 to be pivoted into a raised position illustrated by the dot and dash lines 30', in Fig. 7 to strike upon the bottom face of the narrow baffle plate 20. Striking the cover sheet 30 against this baffle plate will cause it to jar loose any sludge deposits which have accumulated on the top face of the cover sheet thus permitting the water to freely wash them down the inclined surface and off the cover sheet 30.

In other respects this form of the invention is similar to that previously shown and like reference numerals identify like parts in each of the several views.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A fire tube boiler, comprising a boiler casing for holding and circulating a quantity of water and for generating steam, a combustion chamber located in the bottom portion of said casing having a burner and a downwardly sloping top crown sheet, rectangular fire tubes spaced from each other, located at desired positions, and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate.

2. A fire tube boiler, comprising a boiler casing for holding and circulating a quantity of water and generating steam, a combustion chamber located in the bottom portion of said casing having a burner and a downwardly sloping top crown sheet, rectangular fire tubes spaced from each other and extending upwards from said

crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, said fire tubes being adapted to transfer heat passing therethrough into the water to assist in heating the same, and being so arranged as to permit a very narrow body of water therebetween, surrounded by a comparatively large heating surface of the boiler tubes.

3. A fire tube boiler, comprising a boiler casing for holding and circulating a quantity of water and generating steam, a combustion chamber located in the bottom portion of said casing having a burner and a downwardly sloping top crown sheet, rectangular fire tubes spaced from each other and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, said fire tubes being adapted to transfer heat passing therethrough into the water to assist in heating the same, and a water inlet and a steam outlet.

30 4. A fire tube boiler, comprising a boiler casing for holding and circulating a quantity of water and generating steam, a combustion chamber located in the bottom portion of said casing having a burner and a downwardly sloping top crown sheet, rectangular fire tubes spaced from each other and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, said fire tubes being adapted to transfer heat passing therethrough into the water to assist in heating the same and a water inlet and a steam outlet, said baffle plates being extended rearwards from the front wall of said boiler casing.

5. A fire tube boiler, comprising a boiler casing 50 for holding and circulating a quantity of water and generating steam, a combustion chamber located in the bottom portion of said casing having a burner and a downwardly sloping top crown sheet, rectangular fire tubes spaced from each other and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, said fire tubes being adapted to transfer heat passing therethrough into the water to assist in heating the same, a water inlet 60 and a steam outlet, said baffle plates being extended rearwards from the front wall of said boiler casing, said latter baffle plate being formed of rearwardly extending finger portions which extend between adjacent faces of said fire tubes.

6. A fire tube boiler, comprising a boiler casing for holding and circulating a quantity of water and generating steam, a combustion chamber located in the bottom portion of said casing and having a burner and a downwardly sloping top 75 crown sheet, rectangular fire tubes spaced from

each other and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, said fire tubes being adapted to transfer heat passing there-through into the water to assist in heating the same, a water inlet and a steam outlet, said baffle plates being extended rearwards from the front wall of said boiler casing, said latter baffle plate being formed of rearwardly extending finger portions which extend between adjacent faces of said fire tubes, a cover sheet of rigid metal hinged upon said crown sheet, and means to cause said cover sheet to strike against said narrow baffle plate.

7. A fire tube boiler, comprising a boiler casing for holding and circulating a quantity of water and generating steam, a combustion chamber 10-

5 cated in the bottom portion of said casing for a burner and having a downwardly sloping top crown sheet, rectangular fire tubes spaced from each other and extending upwards from said crown sheet to the top of said casing, a smoke hood mounted on the top of said casing for connecting said fire tubes with a chimney, a narrow baffle plate mounted within said casing slightly above the high end of said crown sheet, and a wider baffle plate mounted within said casing above said narrow baffle plate, a cover sheet of rigid metal hinged upon said crown sheet, means for causing said cover sheet to strike against said narrow baffle plate, said means comprising a rod positioned adjacent the low end of said cover sheet, said cover sheet being fixedly attached to said rod, and said rod being extended at one end to the exterior of said casing through a packing gland, and means for gripping said end to turn said rod.

HOWARD G. SAWYER.
